UNITED STATES PATENT OFFICE.

FREDERICK BLETZINGER, OF CHICAGO, ILLINOIS.

SODA-FOUNTAIN.

SPECIFICATION forming part of Letters Patent No. 765,374, dated July 19, 1904.

Application filed January 21, 1903. Serial No. 139,966. (No model.)

To all whom it may concern:

Be it known that I, FREDERICK BLETZINGER, a resident of Chicago, in the county of Cook and State of Illinois, have invented certain new and useful Improvements in Soda-Fountains, of which the following is a specification.

This invention relates to improvements in soda-fountains, and refers more specifically to an improved fountain in which the extract-receptacles are in the form of jars largely exposed and so mounted within or upon the fountain as to be capable of tilting for the purpose of pouring out the contents.

Among the salient objects of the invention are to provide a construction in which the extract-receptacles are largely exposed to view and are brought into full view each time they are used, thereby not only enhancing the appearance of the fountain, but insuring proper care and attention in the matter of cleanliness; to provide a construction in which the extract-receptacles may be reliably secured in a tilting frame, so that they are not liable to become disengaged and broken, but at the same time are made capable of being incidentally detached and removed with the utmost convenience; to provide a construction in which, notwithstanding the jars or extract-receptacles are movable in the manner described, yet their lower ends are nevertheless inclosed within a refrigerating-chamber at all times except when tilted into pouring position; to provide a construction of the character last referred to in which the refrigerating-chamber remains substantially closed during the tilting movement of the extract-receptacles, and, in general, to provide a simple, efficient, and ornamental construction in soda-fountains.

To the above ends the invention consists in the matters hereinafter described and more particularly pointed out in the appended claims, and the invention will be more readily understood from the following description by reference to the accompanying drawings, forming a part thereof, and in which—

Figure 1 is a perspective view of the principal portions of a soda-fountain embodying my invention. Fig. 2 is a detail, partly in

transverse vertical section and partly in side elevation, of the parts concerned in the present invention. Fig. 3 is a front elevation of a plurality of the extract-jars, the stationary supporting-frame upon which the jars rest being shown in longitudinal vertical section. 55 Fig. 4 is a horizontal sectional view taken through one of the jars on the line 4-4 of Fig. 3 and looking downwardly. Fig. 5 is a fragmentary front elevation of the lower end portion of one of the jars with the supporting-frame removed.

Referring to the drawings, 1 designates as a whole the main frame of the fountain structure, of which, it will be understood, only those parts which are concerned in the support of the extract-receptacles are shown, these parts comprising the front wall 2, back wall 3, and a horizontal partition 4. The front wall terminates at its upper end in a counter-like ledge member 5, which in the preferred construction shown herein is coincident in height with the horizontal partition 4, within which the extract-receptacles (designated 6) are seated and supported.

In the approved form shown each receptacle is a jar, preferably transparent, approximately rectangular in cross-section, of greater depth from front to rear than its width, and of substantially uniform size throughout its height, this form, as will hereinafter appear, 80 being economical of space and more conveniently handled than would be a cylindric or equilateral jar. Each jar is provided with a cover 7, hinged to the jar at its rear side, as indicated at 8, and provided also with a handle 7', whereby the jar may be readily tilted. Each jar is also provided at its front side, at the upper end thereof, with a spout extension 9, desirably extending across the principal width of the jar and provided with a lateral 90 opening, as indicated at 10, which is controlled by a depending flap or gate 11. The gate 11 is hinged to the front edge of a plate-like extension 12, which is formed integrally with a metal rim 13, which encircles the upper edge 95 of the jar and forms the support for the hinge 8, the plate-like extension 12 forming a permanent closure for the upper side of the spout

extension 9, which said upper side is made flush with the lower edge of the rim 13. The several gates 11 form a convenient and ornamental support for the labels designating the 5 contents of the several receptacles, as shown clearly in Fig. 3, and in order that the gates may be manipulated conveniently they each terminate at their lower ends in a suitable handle 14.

10 Describing now the means whereby the receptacles are tiltably supported in the fountain structure, 15 designates a supporting-bar mounted upon the inner edge of the ledge 5, and 16 designates a second transversely-extending supporting-bar arranged parallel with the front bar 15 and at a point some distance in rear of the rear sides of the receptacles 6, the supporting-bar 16 being secured at its ends to the end walls of the fountain structure. At distances apart equal to the face width of the receptacles 6 are arranged a plurality of cross-bars 17, as best shown in Fig. 3, which bars are desirably of approximately T shape in cross-section, so as to afford sufficient rigidity and provide lateral flanges 18, which engage the proximate sides of the receptacles and confine the latter against side-wise movement.

15 Each receptacle 6 is mounted within and has attached to its lower end a basket-like frame (designated as a whole 19) comprising a circumferential band 20, located at a level coincident with the supporting-bars 15 and 16, a second circumferential band 21, located near the lower end of the receptacle, and a stirrup-like strap 22, united at its upper ends with the band 20 and extending thence downwardly and around the bottom of the receptacle, as seen clearly in Figs. 2 and 3. The receptacle 40 is slightly enlarged, so as to provide a circumferential shoulder 6' immediately above the band 20. Upon the band 20 at points approximately coincident with the front side of the receptacle and at each side thereof is secured 45 a pivot-ear 23, provided with a lateral projecting pivot-stud 24, which engages and rests within a slotted bracket member 25, rigidly mounted upon the front supporting-bar 15.

50 The body of the receptacle depends below the pivotal axis formed by the pivot-studs 24 a distance equal approximately to nearly one-half the full height of the jar, and it follows, therefore, that when the receptacle is tilted up into horizontal or approximately horizontal 55 position, as indicated in dotted lines in Fig. 2, said lower end will project back a considerable distance beyond the plane occupied by the rear side of the receptacle when in upright position. The supporting-bar 16 is accordingly located far enough in rear of the receptacles to be out of the path of the latter when thus tilted, and in order to cover the space between the rear sides of the receptacles and said supporting-bar extension-plates 26 are 65 secured to the receptacles, said plates being in

the present instance shown as formed integrally with the supporting-band 20 of the several receptacles.

It will be understood that the lower part of the fountain, within which the lower ends of the extract-receptacles depend, constitutes a refrigerator - chamber, and the extension-plates 26 serve to keep this chamber normally closed. For the same reason the front side of the band 20 is provided with a lip-like extension 27, which normally underlies the supporting-bar 15, as indicated clearly in Fig. 2, and closes the refrigerating-chamber at this point.

28 designates a removable closure, which 80 closes a filling-aperture formed in the partition 4 at a point in rear of the supporting-bar 16, through which aperture ice may be charged from time to time, and in order to prevent the ice from filling in around the bottoms of 85 the extract-receptacles, so as to prevent the free movement of the latter, a curved depending partition or guard 29 is provided, which is arranged to extend from the supporting-bar 16 downwardly to a point adjacent to the lower 90 ends of the receptacles.

It is at times necessary to remove the receptacles from the fountain, and means are provided for disconnecting it from its basket-like frame, so that the latter need not be disconnected from its supports. Furthermore, it is necessary that the basket-like frame 19 be so secured to the receptacle that the latter may be tilted into horizontal position without danger of becoming dislodged therefrom. Accordingly the receptacle is provided at points in register with the lower band 21 of the frame 19 at its front and rear sides with grooves 30 and 30', (see Figs. 4 and 5,) suitably shaped to receive or in part receive said band 105 21, and the latter, as best shown in Fig. 2, is provided at its rear side with a set-screw 31, threaded through the band and arranged to engage the groove at the rear side of the receptacle and at the same time throw the band 110 rearwardly, so as to cause its front side to reliably engage the groove. The receptacle being of uniform size throughout its portion which extends within the basket or frame may therefore be freely lifted out of the latter when the set-screw is retracted and the encircling band 20 shifted forward sufficiently to disengage it from the front groove, it being noted that, as clearly shown in Fig. 4, the internal width of the band 20 from front to 120 rear is slightly greater than the outside diameter of the receptacle.

115 In order that the several receptacles may be arrested and held in vertical position, each is adapted to engage at its lower end with a 125 stop or buffer 32, mounted in the front wall 2, as shown clearly in Fig. 2. In the preferred construction shown herein said buffers consist of plungers 33, slidably seated in a suitable socket 34 and normally held projected 130

by means of coiled expansion-springs 35, the inner headed end of each plunger being adapted to engage the front side of the band 21 of the corresponding receptacles.

5 The operation of the apparatus is entirely obvious from the foregoing description and need not therefore be described in detail. It is sufficient to say that the operator desiring to draw extract from any one of the receptacles first lifts up the gate 11, so as to open the spout, and then takes hold of the knob 7' and tilts the receptacle forwardly until the required extract has been poured out. As the jar is tilted forwardly the extension-plate 26 is carried upwardly, thus momentarily opening the space immediately in rear of the jar; but inasmuch as the bottom of the jar swings into this space the loss of cold air is inconsiderable. It will be obvious that when the jar 20 is thus tilted it will be almost entirely exposed to view, and it follows that the fountain must of necessity be kept clean and free from sediment. Upon the return of the jar to its upright position the cushioning-buffers prevent 25 danger of breaking the jar and arrest the latter when it has reached a perpendicular position. The disconnection of the jar and its removal when it is necessary to clean the same has been described and need not be repeated.

While I have herein shown and described a preferred embodiment of the invention, yet it will be understood that the details of construction may be modified without departing 35 from the invention. I do not therefore limit myself to the details of construction shown and described except to the extent that they are made the subject of specific claims.

I claim as my invention—

40 1. In a soda-fountain, the combination of a fountain structure having a front wall provided at its upper edge with a series of extract-receptacle supports a cooling-chamber in rear of said front wall, a recess immediately 45 in rear of said receptacle-supports and extending into said cooling-chamber, and a series of partly-exposed extract-receptacles tiltably and removably mounted upon said supports to oscillate within said recess upon transversely-extending axes located approximately 50 at the front sides of the receptacles and intermediate the heights of the latter, whereby said receptacles are brought into a fully-exposed horizontal position above said structure when tilted, substantially as described.

55 2. In a soda-fountain apparatus, the combination with a fountain structure provided with a front wall, and a series of extract-receptacle supports arranged at the upper edge 60 of said front wall, a recess constituting a part of a cooling-chamber and located immediately in rear of the upper portion of said front wall, and a series of extract-receptacles tiltably and removably mounted upon said receptacle-supports upon transversely-extend-

ing axes located intermediate the heights of the receptacles whereby the lower ends of the latter will extend within said cooling-chamber when in upright position, and swing upwardly through said recess into fully-exposed 70 view above said structure when the upper ends thereof are tilted forwardly for drawing extract, substantially as described.

3. In a soda-fountain apparatus, the combination with a fountain structure having a 75 front wall forming the front side of the cooling-chamber, a series of pivot-supports arranged at the upper edge of said front wall, a series of extract-receptacles pivotally connected with said pivot-supports upon axes 80 arranged intermediate the heights of the receptacles and at the front sides thereof, the portions of said receptacles located above said pivot-supports being freely exposed and their lower ends arranged to extend within said 85 cooling-chamber, and means normally closing the upper side of the cooling-chamber contiguous to the rear sides of the receptacles, opening automatically upon the tilting of the receptacles, substantially as described. 90

4. In a soda-fountain, the combination of a fountain structure, the base of which is provided with a substantially flat top portion, the space immediately below which constitutes a cooling-chamber, a series of receptacle-supports arranged to extend transversely along said flat top near the front side thereof, a series of extract-receptacles pivotally connected with said supports so as to be capable of tilting in vertical planes extending from front to 100 rear and whose pivotal axes are located at points intermediate the heights of the receptacles and movable closures connected with and moving with said several receptacles, said closures serving to normally close the tilting 105 space occupied by the receptacle when tilted, substantially as described.

5. In a soda-fountain, the combination with a refrigerating-chamber and a suitable pivot-support located adjacent said chamber, of a 110 transparent extract-receptacle mounted upon said pivot-support to swing upon an axis located midway of the height of the receptacle and adjacent to or in the front plane of the receptacle, the base of said receptacle being 115 arranged to extend within said refrigerating-chamber when the receptacle is in its normal position and to swing into fully-exposed position above said chamber when turned upon said pivot-support, for the purpose set forth. 120

6. In combination, a soda-fountain receptacle provided intermediate its height with outstanding circumferentially-extending shoulders, a supporting-ring encircling the body of the receptacle and engaging said shoulders, 125 pivot-supports upon said ring, and an adjustable clamp connected with said ring, comprising a second band encircling the body of the receptacle at a point below the supporting-ring, grooves formed in the body of the 130

receptacle to receive said lower encircling ring, means for holding said clamping-ring in clamping engagement with the body of the receptacle, and connections connecting the 5 supporting and clamping rings.

7. A soda-fountain receptacle provided at its upper end with a laterally-projecting spout, a rigid plate forming a closure for the upper side of said spout, and a pendulous flap hinged 10 to said plate and forming a closure for the lateral opening of said spout, substantially as described.

8. A soda-fountain receptacle provided at its upper end with a laterally-projecting spout, 15 a rigid plate forming a closure for the upper side of said spout, and a pendulous flap hinged to said plate and forming a closure for the lateral opening of said spout, said flap being provided with a label-holding receptacle, substantially as described.

9. In a soda-fountain, a fountain structure proper with a series of rectangular openings in the top surface thereof, a series of pivot-supports mounted near the edges of said openings, a series of extract-receptacles, each provided with a pair of pivot-studs intermediate 25 its ends and adjacent to its front surface, and

a plate-like extension at its rear surface, mounted within said openings and upon said pivot-supports, whereby the greater portion 30 of each receptacle projects above the top surface of the fountain structure and is adapted to be tilted into approximately horizontal position above said top surface, and a buffer mounted within said structure at a point below the pivotal supports and adapted to engage the lower end of the receptacle and hold it in upright position.

10. In combination with a soda-fountain base, having a substantially flat top portion, 40 and a series of extract-receptacles seated to depend at their lower ends through said flat top and pivotally supported upon axes approximately coincident with the flat top, of a curved partition-plate extending downwardly 45 within the base contiguous to, and approximately coincident with the path of movement of the lower end of the receptacle when oscillated upon their pivot-supports, for the purpose set forth.

FREDERICK BLETZINGER.
